UNITED STATES PATENT OFFICE.

ROBERT R. CHILDS, OF ROANOKE, VIRGINIA, ASSIGNOR OF ONE THIRTY-SECOND TO J. L. EARLY, OF SALTVILLE, VIRGINIA; ONE-SIXTEENTH TO W. H. WOODS, OF SALEM, VIRGINIA; ONE SIXTY-FOURTH TO L. M. WOODS, OF SALEM, VIRGINIA; THREE SIXTY-FOURTHS TO J. T. LAYMAN, OF AMSTERDAM, VIRGINIA; ONE THIRTY-SECOND TO HERMAN JAKOBSSON, OF TAKOMA PARK, MARYLAND; AND ONE-SIXTEENTH TO C. T. LAYMAN, OF LAFAYETTE, VIRGINIA.

ADVERTISING AND DISPLAY DEVICE.

Application filed September 17, 1924. Serial No. 738,961.

This invention relates to advertising devices, particularly those of the automatic movable type, and has for its object the provision of a novel advertising device designed particularly for use by tailors, clothing dealers, modistes and others for the purpose of making a very attractive exhibition of different styles in suits, dresses, coats, hats and other garments, or in fact any desired articles.

An important and more specific object is the provision of an advertising mechanism including a display cabinet provided with means whereby a series of dummies may be caused to make their appearance at intervals, the dummies being dressed in the particular garments to be exhibited so that a very clear indication may be given as to the particular styles or the like.

Another object is the provision of a device of this nature provided with means whereby only one dummy will be exposed to view at a certain time, the others being entirely concealed by an automatically operated curtain arrangement so mounted with respect to the other parts of the apparatus that it will open and close periodically in accordance with the positions of the dummies.

The invention further contemplates the provision of means whereby the dummy will, after travelling out of the cabinet along a suitable runway, be caused to turn around several times in order that all portions of the model garments may be inspected and whereby the effect from all different angles may be seen.

The invention has for a further object the provision of a cabinet structure and movable means embodying various detailed features which will greatly enhance the attractiveness so that the device will be a real ornament when set up and operated in a show window or other place.

An additional object is the provision of an advertising device of this character which will be simple and inexpensive in manufacture, continuous and automatic in operation as long as power is applied, positive in action, efficient and durable in service

and a general improvement in the art. 50

With the above and other objects and advantages in view, the invention consists in the details of construction and arrangement of parts to be hereinafter more fully described and claimed, and illustrated in the accompanying drawings, in which:

Figure 1 is a perspective view of the complete device;

Figure 2 is a horizontal section taken above the runway;

Figure 3 is a somewhat diagrammatic perspective view showing the travelling chain arrangement together with the operating means therefor, this view also illustrating a plurality of dummies;

Figure 4 is a detailed cross section showing the mounting for the dummies and the guides therefor;

Figure 5 is a detailed fragmentary horizontal section showing the means for operating the curtains;

Figure 6 is a detailed section on the line 6—6 of Figure 5;

Figure 7 is a perspective view showing the curtains and operating members therefor. 75

Referring more particularly to the drawings, the numeral 10 designates the cabinet as a whole, which cabinet may be of any desired size, shape and materials and ornamented in any preferred manner depending upon the contemplated cost and the taste of the manufacturer. The cabinet includes the lower portion 11 which constitutes a housing for the operating mechanism, and it further includes an upper portion 12 having a floor 13 upon which is mounted a rectangular partial enclosure or wall structure 14 representing a room and provided at opposite ends or sides with openings 15 and 16. The front of the upper portion 12 of the cabinet is formed with a door opening 17 near which the forward edges of the side walls of the room structure terminate.

Mounted at the front of the cabinet and in the same plane with or formed as a continuation of the floor 13 is a runway 18 which projects considerably beyond the front of the cabinet for a purpose to be described.

The floor 13 and runway 18 are formed with a single continuous slot 19 which defines a T-shaped trackway beneath which are secured angular or flanged guides 20. Located at the corners of the trackway are sprockets 21 mounted upon shafts 22 suitably journaled through the floor 13 or through any other supporting means. Trained about all of these sprockets as clearly indicated in Figure 3 is an endless chain 23.

For driving the chain, use may be made of any preferred power device, though in the present instance I have shown a suitable electric motor 24 having its shaft 25 carrying a worm 26 meshing with a worm wheel 27 on one of the shafts 22. Any control mechanism for regulating the speed of the motor may be provided but such is not shown as it forms no part of the present invention.

The chain 23 carries a plurality of dummies 28, each of which is here shown as mounted upon a rod or spindle 29 journaled in an angular bracket 30 suitably mounted on the chain. Each rod or spindle carries a disc 31 and a spur gear or pinion 32. Any desired number of dummies may be provided located at any desired distances apart along the chain and it will be observed that the rod or spindles 29 pass through and are adapted to travel along the slot 10 when the chain is driven, the discs 31 being disposed within the guides 20 for not only preventing up and down movement of the dummies but for steadyng them at all times and preventing any lateral shaking or rocking.

Mounted within the runway 18 at the forward extremity thereof is an internal segmental gear or an arcuate rack 33 with which the pinion 32 of each rod 29 meshes as the successive dummies reach the end of the runway, the purpose being to cause rotation of the dummy so that all sides may be inspected. In actual practice the various dummies may be differently dressed so as to give an accurate portrayal of the styles in suits or other articles or garments handled by the dealer using the device.

Mounted above the door opening 17 in the upper portion 12 of the cabinet is a guide rod 34 from which are suspended curtains 35 which have their upper ends secured to metallic or other rigid strips 36 equipped with guide rings 37 or the like slidale on the rod 34 so that the curtains will be capable of movement out of or into obstructing relation to the opening 17. Slidale on the rod 34 and secured to the strips 36 near the inner ends thereof are other ring members 38 formed on arms 39 and 40 connected by a coil spring 41 which normally holds the curtains together. Secured to the ends of the arms 39 and 40 are cords or other flexible members 42 and 43 respectively which are trained over suitably mounted guide pulleys or rollers 44 lo-

cated at any necessary points and which have their other ends connected with slides 45 and 46 respectively. I also provide a flexible member 47 trained over guide pulleys 48 at opposite sides of the door opening 17 and connected with the arms 39 and 40 so that when one curtain is pulled open the other will be correspondingly moved into open position, and vice versa. It will be observed that the arrangement of the flexible members and pulleys is such that when either slide is moved toward the curtains the curtains will be slid apart.

Each of the slides 45 and 46 is mounted within a suitable guide 49.

The operating means for moving the slides when opening the curtains consists of spring fingers 50 mounted on the chain 23 in any desired manner at points spaced in advance of the dummies, and these spring fingers project outwardly beyond the chain so as to engage against projections 51 on the slides 45 and 46 whereby to move them to the ends of their guides. These springs are of sufficient strength to carry the slides along until they reach the ends of their guides whereupon the fingers will yield and slip over and pass the projections.

In the operation, it will be seen that when the motor 24 is energized, the chain 23 will be driven so that the series of dummies 28 will move along the trackway. Shortly before a dummy reaches a point near the inside of the curtains 35, one of the spring fingers 50 will engage the projection 51 on the slide 45 and exert a pull upon the flexible member 47 which will result in pulling the associated curtain laterally. Owing to the fact that the arms 39 and 40 of the curtains are connected by the flexible member 47, it is obvious that the other curtain will likewise be moved laterally. In this way both curtains are moved apart against the resistance of the spring 41 and will remain separated until the dummy has passed through the opening 17, at which time the spring finger will slip over and beyond the projection engaged thereby and permit the spring 41 to return the curtains to normal

100 105 110 115 120 125 130

or closed position in which they will remain while the dummy travels along the runway and back again. When the dummy reaches the forward end of the runway it will be rotated owing to the engagement of the pinion 32 with the arcuate rack 33. After the dummy has been thus thoroughly exhibited, it is carried back toward the cabinet and upon approaching the front thereof the spring finger will engage the projection 51 on the slide 46 and exert a pull upon the flexible member 43, thereby again causing the curtains to slide apart so that the dummy may enter the cabinet. This operation is of course the same for each of the successive dummies. The purpose of having the room

structure formed by the rectangular enclosure or the walls 14 is to prevent a view of the mechanism during the short time intervals that the curtains are open for the passage of the dummies into and out of the cabinet.

From the foregoing description and a study of the drawings it will be apparent that I have thus provided a comparatively simple device which is particularly well adapted for display purposes in advertising styles or the like. By dressing the series of dummies in different types of suits or other garments it is obvious that a dealer may display the different fashions or styles as well as types of garments and may also exhibit his stock of different materials. As a matter of fact the field of utility for the device is almost unlimited as it is capable of employment by dealers in widely different kinds of merchandise, there being no limitation as to the employment of dummies inasmuch as articles themselves might be easily carried by the chain if such an arrangement should be found satisfactory or desirable for any reason whatsoever.

While I have shown and described a preferred embodiment of the invention it will be understood that I reserve the right to make all such changes in the form, detailed construction, and arrangement and combination of parts provided such changes constitute no departure from the spirit of the invention or the scope of the subjoined claims.

Having thus described the invention what is claimed is:

1. In a display device, a cabinet equipped with a runway and provided with a door opening, a trackway within the cabinet extending through the door opening and along the runway, an endless member mounted beneath the trackway, means for driving the endless member, a dummy travelling along the trackway and moved by the endless member, a door for said door opening, means for supporting the door for sliding movement in a direction transverse to that portion of the trackway disposed through the door opening, means for normally maintaining said door closed, and automatic means for opening the door at a predetermined time in advance of the exit and entrance of the dummy through the door opening.

2. A display device comprising a cabinet having a door opening, a runway extending in advance of such opening, an endless trackway within the cabinet and extending upon the runway through the door opening, a door for normally closing said door opening, means for supporting said door for sliding movement in a direction transverse to the portion of the trackway disposed through the door opening, means for mov-

ing a dummy along the trackway, and automatic means for moving the sliding door into open position at a predetermined time in advance of the entrance or exit of the dummy through the opening.

3. In a device of the character described, a cabinet having a runway and provided with a door opening, a trackway within the cabinet extending along the runway, an endless member mounted beneath the trackway, means for driving the endless member, a plurality of supports carried by the endless member and movable along the trackway, said supports being adapted to carry dummies, means normally closing the door opening, and means operated by movement of the endless member for opening said second named means including movable elements supported independently of the endless member and the door operatively connected with the second named means, and trips carried by the endless member engageable with said elements.

4. In a device of the character described, a cabinet having a door opening and a runway, a trackway within the cabinet extending along the runway, an endless member beneath the trackway, means for driving the endless member, a plurality of upstanding supports carried by the endless member and slidable along the trackway, means on the runway engageable by the successive supports for effecting rotation thereof upon reaching a predetermined point, said last named means comprising a pinion on each support, and a rack on the runway engageable by the successive pinions.

5. In a device of the character described, a cabinet having a door opening and a runway, a trackway within the cabinet extending along the runway, an endless member beneath the trackway, means for driving the endless member, a plurality of upstanding supports carried by the endless member and slidable along the trackway, means on the runway engageable by the successive supports for effecting rotation thereof upon reaching a predetermined point, said means comprising a pinion on each support, and an arcuate rack located at the forward extremity of the runway and engageable by the successive pinions.

6. In a device of the character described, a cabinet having a door opening and a runway in front of the opening, a trackway within the cabinet extending along the runway, an endless member movably mounted at the bottom of the trackway, a plurality of supports carried by the endless member and movable along the trackway, means for driving the endless member, a pair of slidably mounted closure members for the opening, slides mounted adjacent the trackway and operatively connected with the closure members, and trips carried by the endless

member adapted to engage the slides for moving the closure members to open position.

7. In a device of the character described, 5 a cabinet having a door opening and a runway in advance thereof, an endless member mounted within the cabinet and extending along the runway, means for driving the endless member, a slidably mounted closure 10 member normally obstructing the door opening, slides mounted adjacent the endless member, flexible connections between the slides and the closure member, and fingers carried by the endless member and engageable with the slides for moving the closure 15 member to open position.

8. In a device of the character described, 20 a floor having a continuous slot, flanged guides arranged below the floor at opposite sides of the slot, an endless member movable along the slot, means for moving the endless member, an upstanding rod operatively engaged with the endless member and extending through the slot, a figure carried by 25 the rod above the floor, and a disc carried by the rod extending within the flanged guides to hold the rod in desired position.

9. In a device of the character described, 30 a floor having a continuous slot, flanged guides arranged below the floor at opposite sides of the slot, an endless member movable

along the slot, means for moving the endless member, an upstanding rod operatively engaged with the endless member and extending through the slot, a figure carried by 25 the rod above the floor, a disc carried by the rod extending within the flanged guides to hold the rod in desired position, and means coacting with the portion of the rod below the floor for rotating the rod. 40

10. A display device comprising a cabinet having a door opening and a runway in advance of the opening, a continuous trackway disposed in substantially a T-formation, the stem portion extending through the 45 door opening upon the runway, a member adapted to traverse the trackway, a dummy supported by the member, means for moving the member along the trackway, a door normally closing the opening, automatic 50 means for opening the door before the entrance or exit of the member through the opening, and a wall structure within the cabinet defining a room into which the door opening communicates, said wall structure 55 at opposite sides of the door opening being provided with openings through which the inner portions of the head of the trackway extend.

In testimony whereof I hereunto affix my signature.

ROBERT R. CHILDS.
